MANUFACTURE OF EDGE-LINING STRIPS

Max Spuhr, Essen-Werden, and Hugo Hannes,
Wuppertal-Ronsdorf, GermanyApplication July 15, 1930, Serial No. 468,104, and
in Germany July 18, 1929

2 Claims. (Cl. 26—19)

An application has been filed in Germany July 18, 1929.

This invention has reference to novel means of producing and applying edge-lining strips or the like usually called "passe-poils", braids or the like which are to be attached as a kind of lining to the edges of pieces of wearing apparel, such as uniforms for instance, or to the edges of seams and for other purposes in connection with the clothes making art, and it is intended to devise means of producing new and more durable kinds of articles of this description and to facilitate the method of manufacture thereof. In accordance with the previous art these peculiar kinds of lining blanks were composed of a strip of cloth or other textile fabric of the desired color which was attached to the seam to be protected or lined in this manner or inserted into such seam, by which means a kind of beaded edge was obtained. With this arrangement the sometimes hollow or beaded round head is uniformly projecting from the two parts of fabric connected to each other and to which the strip, braid or blank was secured, so as to constitute an additional protruding edge, sometimes called "passe-poil". With this method of providing such projecting blanks and the like a rather considerable loss of time and material was necessary because the strips referred to had to be cut off from a piece of colored textile fabric or the like, such strips being usually of a width of about 6 tenths of an inch. There is the further inconvenience with this kind of lining blanks as heretofore manufactured that the protruding portion, after the piece of clothing or uniform has been worn for a comparatively short time only, was rubbed through and became of unsightly and untidy appearance.

In accordance with the improvement constituting the subject of this invention a strip of textile fabric, preferably of cloth is provided for, one edge of which is shaped so as to comprise a solid enlargement of substantially round or circular cross-section and which is preferably and most conveniently produced by means of a band-loom with suitably arranged warps and weft threads, the resulting product being then felted on special fulling machines so as to be converted into cloth, and being then colored in the usual manner.

Upon the accompanying drawing we have shown by way of exemplification a fulling device which is particularly suitable for the treatment of the novel kind of lining blank, braid or the like referred to. The device is shown in Fig.

1 in vertical cross section; in Fig. 2 in vertical longitudinal section. For the sake of illustration we have also shown in Fig. 3 the lining blanks referred to as heretofore manufactured; Fig. 4 is a cross sectional view of the new blank, and Fig. 5 shows the same in position as sewn or otherwise inserted between two pieces of textile fabric. Fig. 6 illustrates the arrangement of the warp threads and weft threads in a band-loom.

As appears from Fig. 6 the warp threads 41 are arranged in series in a straight line while the warp threads 42 are disposed around an axis and are enveloped and retained by the fillers or weft threads in the usual manner. The warp threads 41 yield the flat and the warp threads 42 the thickened or enlarged portion of the new lining blank which is obtained in endless strips and is wound into yarns or hanks. Such hanks are fulled in the new fulling device according to this invention, shown in Figs. 1 and 2, so that the article assumes a felted, cloth-like structure and appearance.

The new working device comprises a tank or other container 1 with the fulling liquor 2 into which the hanks 3 of the new lining blank which are passed over the lower roller 4 and upper roller 5 are immersed. The roller 4 is mounted upon two rockable levers 6 and is somewhat rotatable in its bearings 7. The levers 6 are rocked on stationary pivots 8 and are suspended from cords 9 which are passed over the stationary supported guide rollers 10. The ends of the cords are provided with weights 11 which compensate only a portion of the weight of the levers 6 and of the roller 7 to a sufficient extent to cause the hanks to be suitably tensioned. One of the levers 6 may be detached from the roller 4, in order to allow of the hanks being passed over the roller 4. In case of the roller 5 being stationary supported, the hanks may be applied by swinging the cover of the bearing 12 into the open position and then lifting the studs 13 of the roller 4 from the bearings and swinging the roller 4 into the proper position. Upon the same supports 14 in which the roller 5 is mounted the rollers 15 and 16 are arranged which are forced against the roller 5 by the springs 17, 18 so that these rollers are displaceable in suitable guides with relation to the periphery of the roller 5. This roller is driven from a counter-shaft 22 by means of a belt driving train 23, 24, 25, cooperating with the belt driving train 27, 28, 29 with conical adjusting collars or disks, so that the number of revolutions of the shaft 26 may be changed and adjusted. The roller 15 has no particular

105
110

driving means, but it is frictionally driven by the friction produced by the hanks of lining blanks, braids and the like, and it may be arrested by a braking disk 30 with brake band 31 and weight 32.

The fulling action is due to the fact that the hanks of the lining blanks 3 after having been circulated by the roller 5 in the direction of the arrow are undergoing a resistance on the roller 10 15 which produces a jolting action on the fibres, and a similar action is produced by the roller 16 which is operated with lower peripheral speed than the roller 5. As a result of this rubbing, jolting and hammering action, a condensation 15 and felting is effected which imparts a cloth like structure and appearance to the strips of lining blanks. Inasmuch as the hanks contract and become shorter as a result of the jolting action, the rollers 4 and 5 will move towards each other 20 25 in the course of the fulling operation, this movement on account of the compensating weight 11 being without influence upon the operation of the fulling device.

It should be understood that the invention is not restricted to the particular embodiment and arrangement of parts herein shown by way of illustration and it may find expression in other kinds of embodiments of its principle and with-

out thereby deviating from the purview of the invention as expressed in the appended claims.

We claim:—

1. The method of producing a passe-poil lining strip which consists in forming a fabric strip having one edge of tubular formation with its sides collapsed one on the other to form a double thickness at said edge, uniting the ends of the strip to form an endless band, supporting the band in elongated loop formation under tension, causing the band to travel in the manner of a driving belt, and simultaneously producing pressure and friction on the band at a point in its travel. 80 85

2. The method of producing a passe-poil lining strip which consists in forming a fabric strip having one edge of tubular formation with its sides collapsed one on the other to form a double thickness at said edge, uniting the ends of the strip to form an endless band, supporting the band in elongated loop formation under tension, causing the band to travel in the manner of a driving belt, causing the band to pass in its travel through a moistening medium, and simultaneously producing pressure and friction on the band 90 95 100 at a point in its travel.
